(57) **CLAIM**

I claim the ornamental design for a medical tube holder, as shown and described.

DESCRIPTION

FIG. 1 is a perspective view of a medical tube holder, showing my new design in a fully-extended position;

FIG. 2 is a rear perspective view of FIG. 1;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a left-side elevational view of FIG. 1;

FIG. 8 is a right side elevational view of FIG. 1;

FIG. 9 is a front perspective view thereof in a partially-extended position

FIG. 10 is a rear perspective view of FIG. 9;

FIG. 11 is a perspective view thereof, illustrated in a fully collapsed position; and,

FIG. 12 is a perspective view thereof, illustrated in a partially-collapsed position.

The broken lines showing a tube in FIG. 10 depict environmental matter and form no part of the claimed design.
